UNITED STATES PATENT OFFICE

IRVING H. FOWLE, OF DORCHESTER, MASSACHUSETTS

CONTAINER

Application filed March 19, 1928. Serial No. 95,832.

The individual food pack such as cupped ice cream having become an established and popular article, the desirability of an individual spoon has been emphasized. Heretofore it has been attempted by many to meet this growing demand by forming some part of the container as a spoon member. Commercially, however, these expedients do not seem to meet with immediate popularity and the consuming public seems to demand a quick and ready implement with which to dispatch its meltable delicacy and satisfy its immediate craving.

The usual independent spoon shipped in bags or like bulk containers with the packs are very unsatisfactory as unreliable for the use of the consumer as the spoons frequently fail to arrive with the packs, or if they reach the vendor are hard to deliver as where the pack is "handed up" or tossed to the purchaser as in bleacher delivery at ball games. These various handlings subject the pack to all sorts of unsanitary conditions against which my invention is a preventative of contamination.

Spoons have been embedded or packed inside the container, but obviously this is inconvenient and involves the user in handling a spoon already overcoated with the content, so that he can not avoid unpleasant messiness in handling. The problem was to deliver an independent separate spoon with the pack and preferably to have it attached. While many forms of attachment are easy, most have involved expense in packing or inconvenience in handling.

My present invention has solved this problem and offers convenience and sanitation without material added expense. As illustrative I will show in the drawings and describe in the specification a very practical embodiment of my invention. Throughout the specification and drawings, like reference characters are employed to indicate corresponding parts, and in the drawings:

Fig. 1 is a sectional view of a pack in accordance with my invention taken transversely of the spoon member.

Fig. 2 is a plan view of such a pack.

Fig. 3 is a fragmentary detail of the spoon and cap engagement with the container.

Fig. 4 shows a double grooved form, and

Fig. 5 a groove and recess or socket variant.

In these drawings I have indicated at 1 a cup or container which may be of any type and having an internal groove 2 pressed into its side wall adjacent the top. This groove is preferably somewhat elongated from the true circular curve.

In this is lodged the cap 3. Over this and diametrically of the cap I dispose a spoon member 4. This member is of a length equal to the diameter of the cap 3 and preferably has its ends rounded to the curvature of the cup 1. The spoon member 4 is therefore not only held in a protected position just within the cup top, but as it lies flat against the cap is so supported as not to be liable to dislodgment. Furthermore, in further combinative relation to the pack, the spoon 4 acts as a strut or brace and adds to the security of the seal and the strength of the pack.

In Fig. 4 I have shown a double groove form in which the spoon groove 2¹ is separate and the spoon 4¹ made somewhat longer, if desired, than the diameter of the cap and sprung in. The form shown in Fig. 5 is a variant in which the recess 2² of the width 80 of the spoon end is pressed out independent of the cap groove.

The ends of the spoon member are preferably arc shaped but may be made slightly eccentric to give a cam effect when engaged with the slot, or recess, by a rotary motion. In assembling, the spoons and caps may be fed separately and assembled in the capping operation, or the spoons may be made slightly adherent to the caps by paraffine or adhesive or covered by a thin covering strip or sheet or may be resilient as of wood and sprung in place as shown in Fig. 4.

Such modifications may be variously developed and combined all without departing from the spirit of my invention.

What I therefore claim and desire to secure by Letters Patent is:

1. In an ice cream pack, a container having an annular interior groove adjacent its top,

a closure disc removably engaging with its edge in said groove, and an independent spoon member above said closure and having its ends lodged in said groove.

5 2. In an ice cream pack, a container having an annular interior groove adjacent its top, a closure disc removably engaging with its edge in said groove, and an independent spoon member having its ends lodged in said groove.

10 3. In an ice cream pack, a container having an annular groove adjacent its top, a closure disc removably engaging with said groove, and a spoon member above said closure and having its ends lodged in said groove.

15 In testimony whereof I affix my signature.
IRVING H. FOWLE.
